UNITED STATES PATENT OFFICE.

HARRY G. TUCKER, OF CHICAGO, ILLINOIS, ASSIGNOR TO NATIONAL FUEL SAVER CORPORATION, OF CHICAGO, ILLINOIS, A CORPORATION OF ILLINOIS.

FUEL-ECONOMIZER DEVICE.

1,122,821.

Specification of Letters Patent. Patented Dec. 29, 1914.

Application filed September 19, 1913. Serial No. 790,683.

To all whom it may concern:

Be it known that I, HARRY G. TUCKER, a citizen of the United States, residing at Chicago, in the county of Cook and State of Illinois, have invented certain new and useful Improvements in Fuel-Economizer Devices, of which the following is a specification.

One of the objects of my invention is to provide a device, to be placed within the breeching, flue or stove pipe of a furnace or stove, whereby to properly pre-heat and then admit the required quantity of oxygen, to the fuel being consumed, to promote combustion and to hold in check, within the furnace, the resulting heat from such combustion, to thereby increase the efficiency of fuel consumption.

Another object of my invention is to provide a very simple efficient and durable device, having no moving parts, adapted to be placed within the breeching, or smoke flue, at one side of the central axis thereof, so as to conserve some of the heat from the escaping hot gases of combustion whereby to heat the ingoing air.

Another object of my invention is to provide a means, for admitting the air within the smoke flue or pipe, that will prevent a violent inrush of air, to thereby impede the draft, and which will divide the air into a series of relatively small streams and thereby distribute it evenly in the gases, into which it is to be entrained.

Other and further objects of my invention will become readily apparent, to persons skilled in the art, from a consideration of the following description when taken in conjunction with the drawings wherein;

Figure 1 shows a furnace, in which my invention is applied. Fig. 2 is an enlarged plan view of the device, showing a part in section. Fig. 3 is a section taken on line 3—3 of Fig. 2. Fig. 4 is a transverse section taken on line 4—4 of Fig. 3. Fig. 5 is a transverse section taken on line 5—5 of Fig. 3.

In all the views the same reference characters are employed to indicate similar parts.

The device 10, as a whole, is divided into substantially two longitudinal members, or lungs 11 and 12, as shown, for the purpose of exposing considerable surface to the heat-

ing effect of the surrounding gases and furthermore to prevent rotation or other rapid movement of the air particles, as they are admitted into the device. It is very desirable that the air, within the device, be as quiescent as possible in order that its passage through the surrounding gases may be more completely and effectively accomplished. I therefore extend the wall of the device, as at 13, down in such a way as to form a substantial partition between the opposite air inlets 14 and 15 so that the streams of air coming through these inlets, may not impinge upon each other, but may be deflected by the wall 16 into the recess 17 and subsequently caused to pass through 70 the narrow throat 18 into the main portion of the respective chamber or lung, as 11 or 12. As the gases pass through these portions of the device, they are brought into contact with the interior surface of the outer walls 13 and against the wall 19 that surrounds the opening 20. The forward end wall, or closure, of the device is tapered, as at 21, and is provided with a series of separated openings 22, for ingress of the air into 80 the heated gases of combustion. Each of the openings, 14 and 15, for admitting the air into the device terminates exteriorly of the flue, in rosettes 23 and 24, each of which is provided with a perforate, separable cover, 85 having a series of separated openings 25. The throat 26, leading from each of the openings 14 and 15, to the respective rosettes 23 and 24, is provided with an opening 27 which lies in a plane along the lower surface 90 of the stove pipe or flue 28, when the device is in place, so that air may also enter these openings, 27—27. The air that passes through these openings has been pre-heated, to some extent, by contact with the lower 95 surface of the flue 28, and that it does pass into these openings, as well as the openings 25 provided in the rosettes, is evidenced by the fact that if a light fabric or paper is held in front of these openings, it will be 100 sucked into them as the result of the suction produced by the ingoing air.

The caps of the rosettes, 23 and 24, are held in place on the main body portion 29 of the structure, by screw bolts 30 and the parts 29 are held in place, on the main structure, by bolts 31. These bolts also serve to assist in holding the device in proper place

within the flue. Other bolts 32, pass through the flue 28, and serve to assist in holding the device in place therein.

The section of the flue or breeching 28 containing the device, is preferably enlarged, and when so formed is reduced at each end, as at 34 and 35, to its normal size, so that the device need not have any choking effect on the outgoing gases, and by this means interfere with the draft.

Carbonic oxide gas, arising from combustion of the fuel, passes out from the furnace to the stack or chimney through a smoke flue, or breeching. If the flue, or breeching, occupies a horizontal position the hotter gases will occupy the upper portion of such conduit, but the conduit will be substantially filled with such gases. Now if air be permitted to enter the flue, in the proper manner, and be properly distributed in the lower portion of the flue, or in one side thereof, it will be rapidly drawn into the midst of the escaping gases and by the processes of diffusion and transpiration of gases, it will be carried back into the furnace, to the point of its attraction, or into the hottest path, which is the most intensely heated combustion point, and the oxygen of the air will intensify the heat generated, and promote the combustion of the fuel. That air does pass into the device in sufficient quantities to promote combustion is evidenced by the fact that all of the doors below the fire, of an ordinary furnace, may be completely closed, and sufficient air, or oxygen, will be supplied through my combustion promoting device to produce intense combustion of the fuel until all of the fuel contained in the furnace has been thus economically consumed.

When air enters the device it is moving slowly and is not permitted to rush into the hot gases while it is in rapid motion and create a draft, in which event it would be

carried out with the escaping hot gases. The correct operation of the device causes the air to assume a quiescent state, and to be thereafter projected into the heated gases,—coming in the opposite direction—toward the furnace, through a series of apertures, thereby dividing the ingoing oxygen into a series of streams, presenting large surfaces for contact with the gases and causing the oxygen to pass through the gases in parallel paths with the moving gases but in a direction opposite to that taken by the gases, to the point of attraction, which is the hottest part of the furnace, or where combustion is most intense. As the oxygen, or air, passes from point to point its progress is through a path of constantly increasing temperature, and it is the increasing temperature that gives direction to the inflowing air.

Having described my invention, what I claim is:—

A device of the character described, comprising a hollow structure substantially divided on a longitudinal, median plane into two chambers; each said chamber having an opening at its rear end registering with openings in the flue in which said device is to be contained, a perforate inlet cap covering each of said openings, a pair of bolts for securing each cap to the flue, said bolts taking through openings in the said structure for holding the same in position relative to the holes in the flue and the inlet caps, and a tapered forward end wall provided with a plurality of apertures common to both chambers, to eject air into the flue in which the device is mounted.

In testimony whereof I hereunto set my hand in the presence of two witnesses.

HARRY G. TUCKER.

In the presence of—

FORÉE BAIN,

MARY F. ALLEN.
